UNITED STATES PATENT OFFICE.

WILLIS A. DARLING, OF NEW YORK, N. Y., ASSIGNOR TO CONTINENTAL RUBBER WORKS,
OF ERIE, PENNSYLVANIA, A CORPORATION OF PENNSYLVANIA.

HANDLE-COVERING.

1,133,622.

Specification of Letters Patent. Patented Mar. 30, 1915.

Application filed June 8, 1914. Serial No. 843,783.

To all whom it may concern:

Be it known that I, WILLIS A. DARLING, a citizen of the United States, residing at New York city, in the county of New York and State of New York, have invented certain new and useful Improvements in Handle-Coverings; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to handle covers for such articles as tennis rackets, fish-poles, golf-sticks, &c., and has for its object the provision of a covering for such handles composed of a soft, resilient material provided with a cloth-like exterior, and with means at each end of such covering to cause the ends thereof to fit the handle snugly.

My invention is illustrated in the accompanying drawings as follows, viz:—

Figure 1, illustrates the handle of a tennis racket with my improved handle covering thereon. Fig. 2, illustrates the handle-grip of a steel fish-pole, provided with my improved handle-covering. Fig. 3, is a longitudinal section of a handle covering made in accordance with my invention, suitable for a tennis racket. Fig. 4, is a like section of a handle covering made in accordance with my invention, suitable for a fish-pole.

In these drawings A, indicates a sleeve of resilient material, preferably rubber, which is preferably molded in suitable shape to correspond with the shape of the handle it is designed to cover, care being taken that it be of slightly less diameter than the diam-

eter of said handle, so that when placed thereupon the material of the sleeve will be slightly stretched. On the interior portion of each end of this sleeve I provide a bead B, of the same material as the body of the sleeve, which causes the termini of the sleeve to tightly bind the handle upon which it is placed.

In making my improved handle covering, the raw rubber is placed upon a suitable core, and is then tightly wrapped with suitable fabric, and is then vulcanized in the usual manner, and when the vulcanization is completed, the fabric is removed, which leaves the imprint of the threads of the fabric in the entire exterior surface of the sleeve, as illustrated by the crossed lines C, in Figs. 1 and 2, the effect of which is a roughened cloth-like rubber surface to be engaged by the hand, which is very agreeable to the touch, and enables the user to obtain a firm grip without excessive muscular effort, while the beads B, at the ends of the sleeve which operate to bind the ends of the sleeve to the handle and prevent accidental rolling-up of the ends of the sleeve.

Having thus fully shown and described my invention, so that others can utilize the same, what I claim as new and desire to secure by Letters-Patent, is:—

A handle covering comprising a seamless sleeve A, having an internal reinforcing bead B, at each end, substantially as and for the purpose set forth.

In testimony whereof I affix my signature, in presence of two witnesses.

WILLIS A. DARLING.
